ATTORNEYS

UNITED STATES PATENT OFFICE.

SAMUEL JACOB AARON, OF BROOKLYN, NEW YORK.

LIGHTING FIXTURE.

Application filed January 25, 1921. Serial No. 439,826.

To all whom it may concern:

Be it known that I, SAMUEL J. AARON, a citizen of the United States, and resident of the city of New York, borough of Brooklyn, in the county of Kings and State of New York, have invented a new and Improved Lighting Fixture, of which the following is a full, clear, and exact description.

10 My invention relates to lighting fixtures with means to provide certain new and useful improvements in connection with a device of this character.

With regard to lighting fixtures it is a well-appreciated fact that it has been customary to provide an outlet box and the hickey associated with the box and serving to couple the fixture to the same. Also it has been necessary to resort to disconnecting, 20 resoldering and insulating the lead wires each time a fixture has been removed or applied. These operations have necessarily involved the services of a skilled mechanic, aside from the fact that an article of this 25 character has not at all times been available to the extent desired, and with this in view I have conceived of a lighting fixture, which may be applied or removed by an inexperienced person without the necessity of 30 opening the feed circuit.

A further object of my invention is to provide a device of this nature which shall be extremely simple in construction and shall present certain improved elements permitting of the accomplishment of the purpose set forth in the preceding paragraph.

Further objects of my invention will appear in the annexed specification and drawings, which latter present one practical 40 embodiment of the same, and in which

Figure 1 is an enlarged cross sectional view of the connection preferably utilized in association with the fixture.

Figures 2 and 3 illustrate details of the 45 same.

Figure 4 is a partly sectional side view of a fixture constructed in accordance with my invention, and

Figure 5 is a bottom plan view of one of 50 the details of the connection.

Having in mind, the essence of my invention, as set forth in the preamble of this specification, I conveniently utilize as a permanent part of a fixture, one portion of 55 a detachable connection, this portion being

positioned adjacent the point of connection normally occupied by the hickey.

Thus, reference being had to Figure 4, it will be seen that the reference numeral 10 indicates any desired type of fixture which 60 includes, in the embodiment illustrated a plug 11, secured adjacent its upper end, which plug is capable of ready association with a socket, whereby to provide means establishing a detachable supporting element, 65 and electrical connection.

Although, as aforesigned, any type of detachable connection may be utilized, for the purpose specified I preferably employ a plug more particularly of the character 70 illustrated in Figure 1. In this view it will be noted that the lead wires 12 of the fixture 10, extend in the usual manner beyond the upper end of the same, but contrary to the conventional construction, a metallic plug 75 13 is secured to the upper end of the fixture 10, and forms a continuation of this element. These two members are secured with respect to each other by any suitable means such as by extending the lower end of the 80 plug 13 to provide a flange 14, a member 15 providing a similar flange being secured to the upper end of the fixture 10.

Also an element in the nature of an insulating washer 16 is preferably interposed 85 between the flanges 14 and 15, and a collar 17 providing insulation 18, encircles this portion and serves to retain the whole in applied position.

Also the body of the plug 13 provides a bore, suitable for the reception of the leads 12, and one of these elements may be conveniently secured to the same by a terminal such as 19, a removable fibre plug 20 formed with an opening 21 closing the upper end of the bore of the plug 13 and serving as a support for the terminal 22 of the second lead 12.

Now with regard to the socket construction preferably utilized, it will be noted that the same conveniently includes a cap 23 attached to the outlet box of the feed leads 24. An insulating plug 25 is arranged below the cap 23 and a ring 26 is preferably interposed between these two elements. However, screws or other suitable securing means 27 may be conveniently utilized for securing these members in their proper position, as well as engaging a metallic shell 28 within 105 which the body of the socket 29 is arranged, 110

1 a layer of insulating material 30 being preferably interposed between these members.

5 It will thus be noted, assuming that one of the feed leads 24 connects with the socket 29, the second lead contacting with the terminal 22, that current will be caused to flow through the leads 12, and with a view of accomplishing this I may preferably recess the body of the plug 25 to provide a communication space for metallic arms 31, furnishing terminals 32 suitable for securing the ends of the leads 24 thereto.

10 It will also be noted that one of the arms 31 extends to a point at which the terminal 15 22 will contact with the same when the plug is properly applied to the socket, and the second arm contacts with the body of the socket 29, thus providing the circuit desired.

15 From the foregoing it will be appreciated that I have provided a lighting fixture which preferably utilizes a detachable connection of the nature described, but not necessarily limited to this form of connection, and by means of which any unskilled person 20 may quickly effect attachment of any desired fixture to any outlet box, and by means of which the fixture will be properly supported and electrical connection will have been established.

25 30 Obviously numerous modifications of structure might readily be resorted to without in the least departing from the spirit of my invention, which I claim as:

35 1. An electrical connecting device comprising a substantially solid metallic block having a threaded plug portion for electrical and mechanical connection with a cooperating socket, said body having an integral flange, and means for permanently connecting said flange to an electric fixture.

40 2. A device recited in claim 1, the body having a longitudinal passage therethrough and a recess at its free end, an element of insulating material lodged in said recess and a center contact mounted on said element.

45 3. A device recited in claim 1, the body having a relatively narrow longitudinal passage therethrough and a recess at its free end, an insulation element lodged in said recess having a face flush with the face of the

free end of the body, and a center contact mounted on said element.

50 5. A device recited in claim 1, the body having a relatively narrow longitudinal passage therethrough, and a lead wire binding post mounted on said body on a face of said passage, said binding post being accessible from the free end of the said body.

55 6. An electrical connecting device comprising a substantially solid metallic block having an interiorly threaded recess capable of receiving the conventional threaded lamp base, said block having an integral flange, an insulating body adjacent the flanged end of said block, a support member adjacent said body, and means for mechanically connecting said block, insulating body and support member into a unitary structure, said means comprising an element frictionally engaging 60 said flange.

65 7. A device affording electrical connection and mechanical support for a heavy electric fixture comprising a substantially solid metallic block having an interiorly threaded recess capable of receiving a conventional threaded lamp base, an insulation body, a support member adapted to be connected to an outlet box adjacent said body, a flange integral with said block, an insulating sleeve surrounding said block, and means for mechanically connecting said block, body and support member into a unitary structure, said means comprising a metallic sleeve enclosing said block and frictionally engaging 70 said flange.

75 8. An electrical connecting and supporting device comprising a support member, an insulating element adjacent said support member, a metallic block contact member adjacent the insulating element provided with a threaded recess and means for holding the support member, insulating element and block in a unitary structure comprising a member frictionally engaging the outside of the block, in combination with a metallic block contact provided with exterior threads cooperating with said threaded recess, said block having a central passageway.

80 85 90 95 SAMUEL JACOB AARON.
